UNITED STATES PATENT OFFICE

155,765

DESIGN FOR A LAMP

Harry Amberg, Rochester, N. Y.

Application October 22, 1948, Serial No. 149,235

Term of patent 7 years

(Cl. D48—20)

To all whom it may concern:

Be it known that I, Harry Amberg, a citizen of the United States, residing at Rochester, in the county of Monroe, and State of New York, have invented a new, original, and ornamental Design for Lamp, of which the following is a specification, reference being had to the accompanying drawing, forming part thereof.

Fig. 1 is a front elevation of a lamp, showing my new design;

Fig. 2 is a left-side elevation;

Fig. 3 is a right-side elevation;

Fig. 4 is a top plan view; and

Fig. 5 is a top plan of the base, taken at a plane approximately at line 5—5 of Fig. 1.

I claim:

The ornamental design for a lamp, as shown.

HARRY AMBERG.
